UNITED STATES PATENT OFFICE.

JOHN F. ALLEN, OF NEW YORK, N. Y.

IMPROVEMENT IN VALVE-GEAR OF STEAM-ENGINES.

Specification forming part of Letters Patent No. 36,695, dated October 21, 1862.

To all whom it may concern:

Be it known that I, JOHN F. ALLEN, of New York, in the county and State of New York, have invented a new and useful Improvement in Steam-Engines; and I do hereby declare that the following is a full and exact description thereof, reference being had to the accompanying drawings, making part of this specification, and to the letters of reference marked thereon.

My invention relates to an improvement in the means of moving the valves in that class of steam-engines in which the steam and exhaust ports are opened and closed by separate valves which slide upon their seats in operating. In these engines it is the usual practice to effect the alternate opening and closing of the ports at opposite ends of the cylinder by connecting the valves rigidly together, so that when one is moved to open the port the other is forced to move with it to the same extent.

An improvement on this mode of operating slide-valves was patented by George H. Corliss. In his improvement the valves are still operated in pairs. The two steam or induction valves, for example, are connected by their rods to two wrist-pins on one wrist-plate, which wrist-plate is secured to a rock-shaft, to which a vibrating motion is imparted by an eccentric, through the intervention of an eccentric-rod and an arm secured to the rock-shaft. The advantage gained by this arrangement is quite limited. The arm to which the eccentric-rod is attached must vibrate in order to impart similar movements to each valve in such an arc that the radius by which it is bisected shall be perpendicular to a line connecting the point of bisection with the center of the shaft carrying the eccentric. The valves, therefore, are not moved independently of each other, but the motion given to each is modified in an important degree by the necessity of giving also a similar motion to the other from the vibration of the same arm, rock-shaft, and wrist-plate.

The object of my invention is to give to the valves, in that class of engines mentioned, a slow motion after the ports have been covered, and at the same time to give to them a motion, while the ports are open, more rapid

than would be imparted to them by the eccentric-rod directly; and it is a further object of my invention to effect each of these results in combination, and in a much higher degree than has hitherto been attained, and also to effect them in nearly the same degree, whatever the throw of the eccentric may be, and at whatever point in the stroke the steam may be cut off.

To these ends my said invention consists in the employment of an eccentric-rod which at a short distance from the eccentric is divided into two rods, which are attached, respectively, to arms secured to separate rock-shafts, by the vibration of which said rock-shafts motion is communicated, through other arms and rods, to separate valves for admitting the steam or for releasing it, or for both purposes, at opposite ends of the cylinder. The two arms on either rock-shaft may be secured in any desired positions relatively to each other, and in this manner each may be caused to vibrate through any portion of a circle, whereby, employing the familiar principle of the toggle-joint, motion in either direction, and either more slow or more rapid than that of the eccentric-rod, in a right line, and this in almost any desired degree, can be imparted to the valve or valves which are operated by one rock-shaft, without being in any manner affected by the similar motion to be given to the valve or valves which are operated by the other rock-shaft.

To enable others skilled in the art to make use of my invention, I will proceed to a description of the same.

In the accompanying drawings, Figure 1 represents a side elevation of a horizontal steam-engine with the cylinder and steam-chest in section, showing the arrangements of the separate exhaust-valves in cavities between the steam-chest and cylinder, and the valve-gear working all the valves separate and independent of each other, operated by a single eccentric, suppressing consequently the steam at a fixed point of the stroke. Fig. 2 represents a top view of the eccentric-strap, showing the manner of attaching two rods to the same. Fig. 3 is a diagram explanatory to the movements of the valve-gear as represented in Fig. 1. Fig. 4 is a diagram explanatory of the movements of the valve-gear,

where said movements are derived from a link, so as to be able to suppress the steam at any desired point of the stroke.

Similar letters of reference denote the same parts in all the figures.

A is the cylinder; B, the piston; C, the steam-chest; F F, the steam-valves on one end of the cylinder, and F' F' the steam-valves on the other end of the cylinder. These steam-valves work on suitable seats, G and G', in the bottom of the valve-chest and perform only the single office of admitting the steam.

In the bottom of the valve-chest C cavities P and P' are made, in which the exhaust-valves H and H' are situated, sliding on the surfaces J and J' on the cylinder A. On each end of the cylinder two openings, M N and M' N', are made, the openings M M' forming passages between the ends of the cylinder through the recesses or cavities P and P' in the bottom of the valve-chest, and the passages m m and m' m', respectively, in the valve-seats G and G' in the steam-chest C, while the openings N and N' communicate with the exhaust-port K, opening to the condenser or atmosphere. These exhaust-valves perform only the single office of releasing the steam, and are formed similar to the usual cup-valves, and are connected to a valve-rod, w, passing through the exhaust passage or port K, and through suitable bosses through the ports M and M', and receive through said rod w a motion independent from the motion of the steam-valves, as will be hereinafter described. By this arrangement any amount of cut-off may be given to the steam-valves, and at the same time the correct exhaust action will under all circumstances be maintained. The steam-valves F F are connected to the valve-rod g, and the steam-valves F' F' are connected to the valve-rod g', and receive through said rods, which are connected to separate levers in the valve gear, as will be hereinafter mentioned, independent motions from each other.

E is the eccentric secured to the crank-shaft L, so as to cut off the steam at the desired point of the stroke.

D is the eccentric-strap, to which two eccentric-rods, O and Q, are attached, connected to separate arms R and S, respectively. These arms R and S are secured on independent rock-shafts, one of which passes through the other, so as to have a common center.

On the end of the shaft on which the arm R is fast another arm, R', is fastened, communicating, through the rod O', connected with the rod g, motion to the valves F F on one end of the cylinder, and on the end of the shaft on which the arm S is fast a crank, S', is fastened, communicating, through the rod Q', connected with the valve-rod g', motion to the steam-valves F' F' on the other end of the cylinder.

The positions of the arms R and S relatively to their respective arms R' and S' are such that said arms R' and S' operate the steam-valves for the purpose of opening or closing the

ports while the same travel a part of an arc having, relatively to the length of arc passed over, a very large versed sine, and act upon said valves after the ports have been closed while traveling through a part of an arc where the versed sine diminishes while the distance of the arc traveled through by the arm increases, and consequently only very little motion is derived in proportion to the amount of travel of the arm or lever. This accelerated motion to one or more valves, while opening or closing the port on one end of the cylinder, at the same time the valves covering the port on the other end of the cylinder receive a very slow motion, while being both derived from one and the same single eccentric, we obtain from the arrangement of the arms R' S', working independent of each other on the opposite sides of the center line, X X'.

In Fig. 1 the piston B is represented at its bottom stroke, and the valves F F, communicating with the passages m m, leading to the bottom of the piston, just about to open.

By reference to the diagram, Fig. 3, it will be perceived that the eccentric stands at the point marked 1 on the shaft, while the crank or arm R', to which the valves F F are connected, stands at the point marked 1 below the center line, X X', which represents the line passing through the center of motion of the rock-shafts, and through the center line of the slide-valve rods, and in which position the valves F F are just ready to open the ports. When the eccentric moves to point 2 around the shaft, the crank R' travels to point 2 on its circle, opening thereby the ports m m to their greatest extent in the short travel through the arc from 1 to 2, and closes the same quite as fast while the eccentric travels from 2 to 3 around the shaft, at which latter position the arm R' is moved back again to point 1 in its arc and has closed the ports again. During the time the eccentric completes the revolution around the shaft from point 3 until it arrives again at point 1 the arm R' is caused to move in its arc from 1 to 5 and back again to 1, traveling through an arc near the center line, X X', and may even pass said line a short distance, as shown in Fig. 4, consequently communicating only very little and a very slow motion during all that time to the valves F F. When the eccentric has arrived at point 4 around the shaft, the piston has traveled through the length of the cylinder, and has arrived at the top end of the same, or nearly so. The eccentric, which, as above described, has operated, through its rod O, the arm R, with which the arm R' is connected, so that the latter has moved the valves F F over the ports m m, operates likewise, through the rod Q, the arm S, to which the arm S' is connected, and has brought, when arrived at point 4 around the shaft, said arm S' to the point 4 in its circle above the center line, X X', in which position the valves F' F' at the top end of the cylinder are on the point of opening the ports m' m' for the admission of the steam in the top end

of the cylinder. When the eccentric arrives at point 5 on the shaft, the arm S' has moved to point 5 on its circle and opens full the ports m' m', and when the eccentric arrives at point 6 on the shaft the arm S' is moved back again to point 4 on its arc and the valves F' F' have closed again the ports m' m'. During the time the eccentric travels around the shaft from point 6 until it arrives again at point 4, and while said eccentric operates through its rod O, the arms R and R', and through the latter the valves F F, as above described, the rod Q of said eccentric acts upon the arm S so as to cause the arm S' to move in the arc from 4 to 2, near the center line, X X', and back again, keeping during that time the valves F' F' over the ports m' m', and communicating only very little and a very slow motion to the same. On either of the rock-shafts an arm or lever is attached, connected, through the rod U, with the valve-rod w, to which the exhaust-valves H and H' are fastened, as above described. This arm is placed in such a position as to work the exhaust-valves in the usual manner.

The exhaust-valves (as here represented) are both connected to one rod, w, in which case the same can be operated by one arm placed on either of the rock-shafts; but when said valves are separated and attached to separate rods they must be operated by separate arms placed on each of the rock-shafts.

The exhaust-valve H' on one end of the cylinder may be connected with the steam-valves F F on the opposite end of the cylinder, and the exhaust-valve H at the bottom end of the cylinder connected with the steam-valves F' F' at the top end of the cylinder, in which case the same motion communicated to the steam-valves will be communicated to the respective exhaust-valves without any separate arms being required on either or on both the rock-shafts for working said exhaust-valves.

Fig. 4 represents a diagram of the valve-gearing of a steam-engine in which the separate movements of the induction and eduction

valves are derived from a link, so as to be capable of adjusting the point of cut-off of the steam-valves according to the load on the engine. The link is slotted in the usual manner and provided with a block capable of sliding in the same, to which the two rods O and Q are attached, which are attached to the separate cranks or arms R and S, secured to separate and independent rock-shafts constructed as above described, and operating the arms R' and S', respectively, and through the same their respective steam-valves, in the manner substantially as above specified. The exhaust-valves derive in this case their motion from a pin, p, fixed in the solid part of the link, connected through the rod V with an arm, T. Another arm, T', attached to the same rock-shaft to which the arm T is fastened, communicates the required motion to the exhaust-valves, by which arrangement any amount of cut-off given to the steam-valves will not interfere with the correct action of the exhaust-valves.

Instead of the above-described arrangement of a split eccentric-rod or two eccentric-rods to one eccentric-strap, an equivalent construction will be two eccentrics set in the same position on the shaft, with their usual straps and rods, or two straps placed upon one and the same eccentric, with rods to each strap and each rod attached to a separate crank.

Having thus described my invention and fully set forth the manner of putting the same into practice, I claim—

The herein-described arrangement of valves worked by means of separate rods and levers operated from the action of a single eccentric, the whole being combined and operated in the manner and for the purpose substantially as set forth.

JOHN F. ALLEN.
